UNITED STATES PATENT OFFICE.

GEORGE A. MACKER, OF MARLBOROUGH, MASSACHUSETTS.

BOOT OR SHOE.

SPECIFICATION forming part of Letters Patent No. 391,478, dated October 23, 1888.

Application filed July 30, 1888. Serial No. 291,469. (No model.)

To all whom it may concern:

Be it known that I, GEORGE A. MACKER, of Marlborough, county of Middlesex, State of Massachusetts, have invented an Improvement 5 in Boots or Shoes, of which the following description, in connection with the accompanying drawings, is a specification, like letters on the drawings representing like parts.

In the manufacture of boots and shoes as 10 now carried on it is customary to place between the pieces constituting the top or quarters of the shoe at its heel end a narrow strip of leather, said strip being stitched in the vertical heel-seam while the latter is being made, the faces 15 of the leather being in contact. The stitching completed, the connected quarters are opened or laid out, and thereafter the projecting portion of the said narrow strip is cut away by means of a tool, and the edge so left is blackened and is rounded by a rubbing action, all 20 these steps being necessary and usual to make a finished seam. In coarse shoes a similar seam is made between the vamp and quarter-pieces.

25 In my efforts to reduce the cost of manufacture of shoes without reducing their strength or durability I have discovered that I may materially cheapen shoes by employing for the filling-piece in the seams referred to a cord 30 enveloped in a narrow strip or band of a material known as "enamel" or "rubber cloth," it consisting of a body of cotton cloth treated and coated at one side to make it black and give it a finish, and preferably make it water-proof, 35 the black color preferably being such as to resemble the leather of the shoe.

My invention in shoes consists, essentially, in the combination, with the upper, of a corded 40 welt-strip inserted in a seam thereof, substantially as will be described.

Figure 1 in side elevation represents a shoe embodying my invention. Figs. 2 and 3, respectively, are sections in the line *x* and *x'*; and Fig. 4, an enlarged sectional detail of the corded welt.

45 The sole *a*, vamp *b*, and quarter-pieces *c* are and may be of usual shape and material. In the heel-seam or in the vertical seam at the rear end of the shoe, and also, as herein shown, in the seam joining the vamp and quarter, I 50 have placed a corded welt, *d*, consisting, preferably, of a cord, 2, over which is wrapped or folded, as in Fig. 4, a strip of india-rubber or enamel cloth, 3, of substantially the color of the material of the boot or shoe and water- 55 proof or water-repellent.

The corded welt referred to, stitched into the seam between the quarter-pieces, or between the vamp and quarter-piece, does not need hammering, blacking, or rounding, and finishing, but presents at all times a finished appearance, and makes a very salable shoe at reduced cost.

60 I claim—

1. The combination, with an upper for boots 65 or shoes having the vertical heel-seam therein joining the quarters, of a corded welt, substantially as described.

2. The combination, with the vamp and 70 quarter-pieces, of the corded welt-pieces inserted in the heel-seam and in the seams between the vamp and quarter, substantially as described.

In testimony whereof I have signed my name to this specification in the presence of two 75 subscribing witnesses.

GEORGE A. MACKER.
